UNITED STATES PATENT OFFICE.

CHARLES LOUIS MEYER, OF OMAHA, NEBRASKA, ASSIGNOR TO CONCRETE ENGINEERING COMPANY, OF OMAHA, NEBRASKA, A CORPORATION OF NEBRASKA.

ADJUSTABLE SHORE.

Application filed September 7, 1926. Serial No. 133,741.

This invention relates to adjustable shores which are adapted for use as temporary supports, particularly in connection with construction operations, for instance, the support 5 of concrete forms or other structures.

Shores of the above type are usually subjected to very rough usage and are used in large quantities in certain operations. Thus the ruggedness of the shores, the simplicity 10 of their manufacture, as well as the ease with which they may be transported, installed or taken down very materially affect the cost of the construction or other operation in connection with which they are used.

15 It is accordingly an object of this invention to provide a simple and rugged shore which may be conveniently transported and installed in position for supporting an object.

It is further and more specifically an object 20 of this invention to provide a shore having a head thereon through means of which such a shore may be readily attached either to the side or the bottom of an object to be supported.

25 With the above and other objects in view, as will be apparent, this invention consists in the construction and arrangement of parts, all as will be hereinafter more fully described in connection with the accompanying drawings wherein:

Fig. 1 is an elevation of a shore embodying this invention.

Fig. 2 is a fragmentary elevational view showing one of the telescopic members of the 35 shore.

Fig. 3 is a fragmentary elevational view of the other telescopic member of the shore.

Fig. 4 is an enlarged plan view of the shore showing the top thereof.

40 Fig. 5 is a fragmentary elevation of Fig. 4.

Fig. 6 is a fragmentary elevation in section showing a modification; and

Fig. 7 is a fragmentary view showing a modified form of head.

45 Referring to the drawings more particularly, numeral 1 designates an elongated cylindrical member having welded to the bottom thereof a plate 2 which acts as a base for the shore. The member 1 which is preferably of

50 metal has drilled therein at the top thereof a pair of diametrical holes 3 which are vertically arranged and in substantially the same plane. In order to facilitate the adjustment, which will be apparent hereinafter, a diametrical hole 4 is drilled intermediate the

holes 3 at right angles thereto. The upper portion of the shore consists of a tubular pipe 5, the inner diameter of which is slightly greater than the diameter of the member 1 so that it may receive the latter therein. The 60 tubular member 5 is provided with a plurality of vertically arranged diametrical holes 6. A suitable pin 7 is used to hold the said members 1 and 5 in relative adjusted position and fits any of the holes 6 in the member 5 65 and the holes 3 or 4 in the member 1.

To the top of the member 5 is welded or otherwise secured a transverse angle bar 8 having a vertically depending flange 9 and a horizontal flange 10. The inner side of the 70 flange 9 of the bar 8 preferably abuts the periphery of the member 5, as viewed in Fig. 4, and is welded thereto to strengthen the connection between the said bar and the said member. The under side of the flange 10 lays 75 across the upper edge of the member 5 and is welded thereto. As viewed in Figs. 4 and 5, the angle bar 8 preferably extends an equal distance on either side of the member 5 and is provided with a plurality of holes 11 which 80 are preferably symmetrically spaced in the flange 10 with respect to the member 5. Similar symmetrically arranged holes 12 are provided in the vertical flange 9.

In the use of the shore it may be readily adjusted in length through means of the pin 85 7 and the holes 3, 4 and 6. The head consisting of the angle bar 8 may be conveniently spiked through means of the holes 11 or 12 to studding or the like forming a part of the 90 forms or the like desired to be supported. The head of the shore may thus be secured at the side of an object desired to be supported or beneath such object or both whichever may be the more convenient or desirable.

The bottom of the tubular member 1, instead of being secured directly to the base 2, may be provided with a jack screw. In Fig. 6 there is shown a member 13 telescopically 100 adjustable in a member 14 similar to the members 1 and 5 respectively in the previous embodiment. A plug 15 is welded or otherwise suitably secured in the bottom of the member 13, a shoulder 16 being provided on said plug, the lower edge of member 1 resting on said shoulder. The plug 15 is provided with a vertical aperture therein which is threaded to receive a jackscrew 17, the latter having a base 18 in which said screw is rotatably secured.

In the use of the latter construction a con- 110

siderable range of adjustment is provided without necessitating removal of the pin 7 and telescopic adjustment of the members 1 and 5. In addition, adjustment is possible 5 through means of the jackscrew 17 after the shore is in place and under a load.

As shown in Fig. 7 the head instead of the usual angle bar 8 may consist of a Z bar 20 similarly secured on the top of the member 19 10 which is similar to the member 5 in the previous embodiment.

I am aware that many changes may be made without departing from the spirit of this invention and I do not wish to be limited to the 15 details shown and described.

I claim:

In an adjustable shore of the telescoping type, a tubular supporting member, and an angle plate secured by one of its legs in a horizontal position to the top end of said member 20 and with its other leg depending and secured along one side of said member, said legs each having apertures therethrough for passage of securing means such as nails whereby said plate may be secured laterally and vertically 25 to the object supported by the shore.

In witness of the foregoing I affix my signature.

CHARLES LOUIS MEYER.
